TURNOVER RECORD CHANGER

Jerald D. Weaver, Fort Wayne, Ind., assignor, by
mesne assignments, to Farnsworth Research
Corporation, a corporation of Indiana

Application May 15, 1942, Serial No. 443,048

10 Claims. (Cl. 274—10)

1

This invention relates to an automatic phonograph and particularly to mechanism for reversing records of different diameters on a turntable and for moving these records from the turntable.

An object of the present invention is to provide an improved automatic phonograph in which both sides of a stack of intermixed records supported on the turntable may be played and thereafter removed from the turntable.

Another object of the invention is to provide improved mechanism for moving a played record from the turntable, reversing it and moving the reversed record back to the turntable.

Another object of the invention is to provide improved record-elevating means for elevating the top record of a stack of records on a turntable.

Another object of the invention is to provide improved record-elevating means which are adapted to be adjusted to elevate the top record of a stack of records on a turntable, regardless of whether the records are of abnormal thickness.

Another object of the invention is to provide improved turntable-elevating mechanism for maintaining the top record on the turntable at a predetermined elevation.

In accordance with the present invention, there is provided an automatic phonograph which includes a rotatable turntable for supporting a record thereon, a pair of movable members positioned beyond the periphery of the turntable and record-engaging means on each of said movable members. The movable members are adapted to be moved in first and second planes. When the movable members are moved in the first plane, the record-engaging means are adapted to be brought into engagement with peripheral edge portions of a record on the turntable. When the movable members are moved in the second plane, they move therewith the record-engaging means and thereby elevate the record thereon from the turntable.

In accordance with another feature of the invention, there is provided an automatic phonograph which includes a rotatable turntable for supporting a stack of records thereon, elevating means for moving the turntable to maintain the top record thereon at a predetermined elevation, a pair of movable members positioned beyond the periphery of the turntable, first means adjustably connected to each of the movable members and second means adjustably connected to each of the movable members and associated with the first means. The movable members are adapted to be moved in first and second planes. When the movable members are moved in the first plane,

2

the first means thereon are moved into engagement with the top surface of the top record on the turntable for adjusting the second means to move between peripheral edge portions of the top two records on the turntable. When the movable members are moved in the second plane, the second means are moved therewith for elevating the top record above the turntable.

In accordance with another feature of this invention, there is provided an automatic phonograph which includes a rotatable turntable for supporting a record thereon, a pair of movable members positioned beyond the periphery of the turntable and record-engaging means on each of said movable members. The movable members are adapted to be moved in first and second planes. When the movable members are moved in the first plane, the record-engaging means are adapted to be brought into engagement with peripheral edge portions of a record on the turntable. When the movable members are moved in the second plane, they move therewith the record-engaging means and thereby elevate the record thereon from the turntable. The automatic phonograph also includes a pair of movable arms which are positioned beyond the periphery of the turntable and first, second and third means which are operatively associated with the movable arms. The movable arms are adapted to be moved by the first means into clamping position with an elevated record on the movable members. The arms are adapted to be moved into a reversing position by the second means and are adapted to be rotated by the third means 180° about their longitudinal axis when they are in the record-reversing position.

In accordance with another feature of the invention, there is provided an automatic phonograph which includes a rotatable turntable for supporting a stack of records. The turntable is adapted to be moved in a plane normal to its plane of rotation. The phonograph also includes a pickup arm for cooperating with a top record on the turntable for reproducing it, connecting means operatively engaging the turntable, manual means associated with the connecting means, driving means and automatic means adapted to operatively connect the connecting means and the driving means. The manual means is adapted to raise and lower the turntable to any predetermined elevation. The automatic means is responsive to the movement of the pickup arm at the end of the reproduction of a record on the turntable for moving the turntable a distance corresponding to the thickness of one record.

For a better understanding of the invention,

together with other and further objects thereof, reference is had to the following description, taken in connection with the accompanying drawings, and its scope will be pointed out in the appended claims.

In the accompanying drawings,

Fig. 1 is a top plan view of the automatic phonograph in accordance with the invention, showing a turntable with a stack of intermixed records thereon and the mechanism for elevating the top record from the turntable. The mechanism for reversing and discarding records on the turntable is shown in section taken on line 1—1 of Fig. 3;

Fig. 2 is a front elevation view partly in section taken on line 2—2 of Fig. 1 showing the mechanism for raising and lowering the turntable and the mechanism for elevating the top record above the turntable;

Fig. 3 is a side elevation view of the upper portion of the automatic phonograph showing a turntable supporting a stack of intermixed records, a magazine in section for receiving the played records and record-reversing and record-discarding mechanism adjacent the turntable;

Fig. 4 is a side elevation view partly in section of the lower portion of the automatic phonograph showing the mechanism for driving the record-moving mechanism;

Fig. 5 is a side sectional view of the record-moving mechanism taken on line 5—5 of Fig. 1;

Fig. 6 is a front sectional view of the record-moving mechanism taken on line 6—6 of Fig. 5;

Figs. 7 and 8 are fragmentary views showing the record-elevating mechanism in different positions during a cycle of their operation;

Fig. 9 is a fragmentary side view showing the record-clamping arms in engagement with an elevated record;

Fig. 10 is a fragmentary view of the mechanism for controlling the elevation of the turntable taken on line 10—10 of Fig. 2;

Fig. 11 is a fragmentary view showing the driving connection between the turntable drive shaft and the main drive shaft taken on line 11—11 of Fig. 2;

Fig. 12 is a view, taken on line 12—12 of Fig. 2, of the cam wheel on the main drive shaft for moving the arms into clamping engagement with an elevated record;

Fig. 13 is a fragmentary view, taken on line 13—13 of Fig. 4, of the main cam wheel and the relationship between the switching member thereon and the means for moving the switching member;

Fig. 14 is a view showing the driving means for reversing a record;

Fig. 15 is a side elevation view partly in section taken on line 15—15 of Fig. 1 showing the pick-up arm and the means for moving the pickup arm;

Fig. 16 is a view, taken on line 16—16 of Fig. 15, showing the driving mechanism for moving the pickup arm and operating the record-elevating mechanism shown in Figs. 2 and 15;

Fig. 17 is a view, taken on line 17—17 of Fig. 2, showing a part of the mechanism for manually raising and lowering the turntable;

Fig. 18 is a fragmentary view showing the control dial for predetermining the elevation of the turntable; and

Fig. 19 is a fragmentary view, taken on line 19—19 of Fig. 18, showing the mechanism for moving the indicator of the control dial shown in Fig. 18.

Referring now particularly to Figs. 1 and 2 of the drawings, the invention here illustrated shows

record-changing apparatus which includes a base plate 15 with a well 16 formed therein. A bracket 17 is suitably fixed to the underside of the base plate 15 and supports a tubular flanged element

18. The element 18, as shown in Fig. 2, is supported in such a manner that it may be moved upwardly relative to the bracket 17. The mechanism for moving the element 18 relative to the bracket 17 will be described hereafter. The upper end of the element 18 is provided with a flanged portion 19 which in turn is provided with a groove or race for guiding a plurality of ball bearings 20. The ball bearings 20 rotatably support a flanged tubular shaft 21 by engaging the bottom of a flanged portion 22 thereof. The shaft 21 also is movable with the element in a vertical plane relative to the bracket 17. The tubular portion of shaft 21 extends downwardly through and below the element 18. The shaft 21 is driven by connecting a suitable driving mechanism to the bottom thereof, not shown in the drawings.

Intermediate the ends of the shaft 21, there is connected thereto a clutch member 23 as shown in Fig. 2. As is evident from Fig. 2, the connection of the clutch member 23 to the shaft 21 permits the clutch member 23 to rotate with the shaft 21 and move relative thereto longitudinally along its axis. Normally the clutch member 23 is in the position shown in Fig. 2.

30 Immediately above the clutch member 23, a clutch member 24 is mounted on the shaft 21 in such a manner that it does not rotate with the shaft 21 except when it is in engagement with the clutch member 23. The hub portion of the clutch 35 24 is provided with a worm gear 25 and is in driving engagement with the gear 26 (Fig. 11) fixed to the shaft 27. The shaft 27 is rotatably supported by the brackets 28 and 28A which are fixed to the bracket 17 in a suitable manner, as shown 40 in Fig. 2.

The mechanism for moving the clutch member 23 into engagement with the clutch member 24, is best illustrated in Fig. 2 and includes a lever 29 pivotally mounted on bracket 28A (Fig. 2). The 45 free end 29A of the lever 29 shuts the clutch member 23. Intermediate the ends of the lever 29, there is connected a core 30 having an upper non-magnetic portion 30A and a lower magnetic portion 30B. The coil 31, supported on extension 28B 50 of the bracket 28A, surrounds the core 30, as shown in Fig. 2, and is adapted to be energized through the conductors 32 and 33 by a tripping mechanism such as that disclosed in U. S. Patent No. 2,018,881. When the coil 31 is not energized, the core 30, the lever 29 and the clutch member 23, are in the position shown in Fig. 2. When the coil 31 is energized, it acts electromagnetically on portion 30B whereby the core 30 is moved upwardly to move therewith the lever 29. The upward movement of the lever 29 is sufficient to move the clutch member 23 into operative engagement with the clutch member 24.

A turntable 34 is fixed to the flanged portion 22 at the upper end of the shaft 21, as shown in Fig. 2, to rotate about the axis of the shaft 21 and to move longitudinally along the axis when the element 18 is moved in a corresponding direction. A stack of records 35 are supported on the turntable 34 and are maintained in a centered position 70 on the turntable by a centering pin 36. This pin extends downwardly through the center of the turntable and the shaft 21 and is suitably fixed in a manner, not shown in the drawings, to be 75 maintained in the position shown in Fig. 2.

Turntable elevating mechanism.

The mechanism for elevating the turntable 34 is best illustrated in Figs. 2, 4 and 10 and includes the element 18 which supports the shaft 21 and the turntable 34. At the lower end of the element 18 there is provided a toothed 37 which is in continual engagement with a threaded portion 38 of a worm gear 39. The worm gear 39 is fixed to one end of a shaft 42 to rotate therewith. Intermediate its ends the shaft 42 is supported by a bracket 41 to rotate relative thereto, preferably in the manner shown in Fig. 2. At the lower end of the shaft 42 there is affixed thereto a miter gear 43 which is adapted to be engaged and driven by a similar miter gear 44 which is fixed to a short tubular shaft 45. The shaft 45 is supported on the shaft 21 in such a manner as to maintain the miter gears 43 and 44 in continual engagement with each other. The shaft 45 normally does not rotate with the shaft 21. The shaft 45 also has affixed thereto a clutch member 49 (Fig. 2). The clutch member 49 is adapted to be engaged by a clutch member 50, which is operatively associated with the shaft 21 to rotate therewith and slide thereon. The clutch member 50 has a groove 51 formed in the hub portion of this member.

The member 50 serves to transmit rotary motion to the member 49. The mechanism for moving the member 50 into driving engagement with the member 49 is best illustrated in Fig. 10. This mechanism includes a spring-biased lever 52 which is pivotally mounted at 52A on the bracket 41 and is biased to the position shown in Fig. 10 by a spring 53 connected between post 41A in bracket 41 and extension 52B of lever 52. The lever 52 is provided with a finger 54 which is in continual engagement with the groove 51 of the clutch member 50. The lever 52 also is provided with a pin 56 which is adapted to cooperate with a cam wheel 55 fixed to the shaft 21 to rotate therewith. In the peripheral wall of the cam wheel 55, there is provided a cam groove 57 with an enlarged area 57A. A member 58 is pivotally connected to the cam wheel 55 in the enlarged area 57A and is provided with heel portions 58A and 58B and a toe 59. The member 58 is connected to the cam wheel 55 in such a manner that it moves only when a positive force is applied thereto. When the lever 52 is in its normal spring-biased position (Fig. 10) and the member 58 is in its dotted-line position shown in Fig. 10, the pin 56 is adapted to be guided by the cam groove 57 during a cycle of operation of the cam wheel 55. When the heel portion 58B engages the pin 56 during this cycle of operation of the cam wheel 55, the member 58 is moved from the dotted-line position to the full-line position shown in Fig. 10. During the succeeding cycle of operation of the cam wheel 55, a toe 59 of the member 58 engages the pin 56 and guides the pin 56 against the tension of the spring 53 from the groove 57 to a position where it is guided by the left wall (Fig. 10) of the cam wheel 55. The pin 56 is guided by the left wall of the cam wheel 55 until the enlarged area 57A again permits it to enter the groove 57 under the tension of the spring 53. As the pin 56 is guided from the groove 57, it engages the heel 58A of the member 58 and moves the member 58 from the solid-line position to the dotted-line position shown in Fig. 10. When the pin 56 is guided from the groove 57 to be guided by the left wall (Fig. 10), the lever 52 is moved in a clockwise direction (Fig. 10) against the biasing action of the spring 53. This clockwise movement of the lever 52, by means of

the finger 54, moves the clutch member 50 into operative engagement with the clutch member 49. With the clutch members 49 and 50 in operative engagement, they are adapted to drive the members 44, 43 and 39 through a cycle of operation. One cycle of operation of the gear 39 raises the member 18 and the turntable 34 a distance corresponding to the thickness of one record.

It is evident that the mechanism for moving the members 49 and 50 into operative engagement with each other is operative only when the pin 56 is moved from the groove 57 to be guided by the left wall of the cam wheel 55. This occurs during a cycle of operation of the cam wheel 55, at the beginning of which the member 58 is in the full-line position shown in Fig. 10. During a cycle of operation of the cam wheel 55, at the beginning of which the member 58 is in the dotted-line position shown in Fig. 10, the mechanism for moving the members 49 and 50 into operative engagement with each other does not function. The apparatus is arranged in such a manner that, at the beginning of a record-discarding cycle of operation of the cam wheel 55, the member 58 is in the full-line position shown in Fig. 10 and at the beginning of a record-reversing cycle of operation of the cam wheel 55, the member 58 is in the dotted-line position shown in Fig. 10.

After the last record on the turntable 34 has been removed and the turntable 34 is raised, then it is in its uppermost position. It is necessary to lower the turntable 34 before the phonograph apparatus is ready to play another stack of records. This is accomplished by mechanism illustrated in Figs. 2, 17, 18 and 19 and which includes a shaft 61. One end of the shaft 61 is supported by the bracket 41 (Fig. 17) and its opposite end is supported by a bracket 62 provided on a portion of the cabinet 63. Intermediate its ends the shaft 61 has provided thereon a knurled portion 61A. Near one end of the shaft 61 there is affixed a gear 64 (Figs. 2 and 17). The gear 64 is operatively associated with a gear portion 65 formed on the hub of meter gear 44 (Figs. 2 and 17). One revolution of the shaft 61 moves the gear 64 and therewith the shaft 61 approximately 120°. On the opposite end of the shaft 61 there is mounted a manual control knob 66 (Figs. 18 and 19). To lower the turntable 34 the knob 66 and the gear 64 must be rotated in a clockwise direction (Figs. 17 and 19). The clockwise movement (Fig. 17) of the gear 64 moves the worm gear 39 in a counterclockwise direction (Fig. 2), to lower the turntable 34. The turntable 34 may be lowered any desired distance depending upon the number of records which the operator wishes to play. The distance the turntable is lowered depends upon the distance an indicator finger 67 is moved relative to an indicator dial 68 (Fig. 18). The indicator finger 67 has a sleeve portion 67A, the left end of which has a knurled portion 67B as shown in Fig. 19. The sleeve portion 67A is mounted on the shaft 61 preferably in the manner shown in Fig. 19 to rotate relative thereto. Each time the turntable elevating mechanism operates to elevate the turntable, as previously described, the shaft 61 and therewith the gear 64 and knob 66 are rotated approximately 120°. This radial movement of the shaft 61 is greater than the distance between two adjacent numbers on the indicator dial 68 (Fig. 18), which is approximately 30°. The mechanism for reducing the movement of the indicator finger 67 relative to the movement of the shaft 61 is shown in Fig. 19. This mechanism includes a shaft 71 fixed on

the bracket 62 and the cabinet portion 63 preferably in the manner shown in Fig. 19. A member 72 with knurled portions 72A and 72B is rotatably mounted on the shaft 71. The knurled portion 72A is in continual engagement with the knurled portion 61A and the knurled portion 72B is in continual engagement with the knurled portion 67B of the member 61A. The diameters of the knurled portions 61A, 72A and 72B and the knurled portion of the member 67A are proportioned so that when the shaft 61 is rotated 120° the finger 67 will rotate 30°. Thus, it is evident that when the turntable elevating mechanism is operated when a record is discarded, the indicator 67 will move to the next succeeding number on the indicator dial 68 (Fig. 18). Also, when the operator manually lowers the turntable, he may turn the knob 66 sufficiently to move the indicator 67 to the number on the dial 68 corresponding to the number of records to be played, and the turntable will be lowered to the proper position to play the top record on the turntable and each succeeding record thereafter.

Pickup arm mounting and mechanism for moving the pickup arm

The mounting of the pickup arm, and the mechanism for moving the pickup arm is illustrated in Figs. 15 and 16. A pickup arm 75 is mounted on a pedestal 76 which is fixed to the base plate 15 at one side of the turntable 34 as shown in Figs. 1 and 15. The pickup arm 75 is mounted in such a manner that it may be moved in a horizontal or a vertical plane. At the free end of the pickup arms 75 there is provided a reproducer or pickup 77 with a stylus 78 which is adapted to cooperate with a record on the turntable 34 to reproduce it. Intermediate the ends of the pickup arm 75 there is pivotally connected thereto a lever 80 in a suitable manner such as shown in Fig. 15. To one end of the lever 80, there is affixed a downwardly extending pin 81. A spring 82 is connected to the pickup arm 75 at 75A and associated with the lever 80 in the manner shown in Fig. 15 to maintain the lever 80 in the full-line position shown in that figure. As will be evident from the description hereafter, when the raised pickup arm 75 is moved from its outwardmost position shown in Fig. 1 toward the turntable 34 and the top record on the turntable is a 12-inch record, the pin 81 will extend in the plane of the 12-inch record on the turntable and serve to position the stylus 78 of the pickup arm 75 over the initial playing groove of that record. As the pickup arm is lowered to bring the stylus 78 into engagement with the initial playing groove of the top record on the turntable, the pin 81 is raised out of engagement with the top record on the turntable in a manner to be described hereinafter to permit the pickup arm to move toward the center of the turntable as the stylus 78 is tracking the playing groove of the top record.

As shown in Fig. 15, the pickup arm 75 is pivotally mounted on a pin 83 which is fixed to a plate 84. The free end of the plate 84 is operatively associated with the lever 80, and the pivoted end of the plate 84 is pivotally connected to a plate 85 by pin 83. This plate 85 is affixed to a tubular shaft 86 which is supported by the pedestal 76 and extends downwardly and below the base plate 15. A lever 87 is fixed to the lower end of the tubular shaft 86 and, when moved in a horizontal plane, is adapted to transmit a corresponding movement to the pickup arm 75. A

spring 88 engages the bottom of the base plate 15 at 15A and is coiled around a pin 88B in such a manner that the free end thereof normally extends in the path of the member 87. When the spring is in its normal position and the lever 87 is moved in a counterclockwise direction (Fig. 15), the lever 87 engages the spring 88 and thereafter is moved against the biasing action thereof. The spring 88 is adapted to be moved out of the path of the lever 87 in a manner to be described hereafter. A pin 89 is provided within the tubular shaft 86 and is adapted to be moved relative thereto in a vertical plane to engage and move the lever 84 for elevating the pickup arm 75 and for moving the pin 81 of the lever 80 into the plane of the top record on the turntable 34. The means for supporting and moving the pin 89 will be described hereafter.

A shaft 90 is mounted on a bracket 91 for rotating relative thereto. A cam wheel 92 is fixed to the upper end of the shaft 90. This cam wheel is cylindrical in shape and is provided with the cam surface 93 around the periphery of its upper surface. The cam surface 93 has cam portions 93A, 93B and 93C. The lower end of the pin 89 is in continual engagement with the cam surface 93 and is supported thereby. Also provided on the upper surface of the cam wheel 92 are members 94 and 95. When the cam wheel 92 is stationary, the member 94 is in engagement with the spring 88 to maintain its free end out of the path of the lever 87. This position of the member 94 in relation to the spring 88 is shown in Fig. 15. When the member 94 is moved with the cam wheel 92 from the position shown in Fig. 15, it is moved out of engagement with the spring 88 and permits the free end of spring 88 to move in the plane of movement of the lever 87. The member 95 extends upwardly from the surface of the cam wheel 92 in the plane of the lever 87 and is adapted to move the lever 87. On the peripheral wall of the cam wheel 92 there is provided a groove 96. Ribbon members 97 are connected to the cam wheel 92 in the groove 96. The opposite ends of the ribbon members 97 are connected to cam members of record-elevating mechanisms which will be described hereafter.

To the lower end of the shaft 90, there is fixed a lever 98 to rotate therewith. The lever 98 is normally biased by a spring 99 to the position shown in Fig. 16. Spring 99 is secured to bracket 28 by pin 99A and is hooked into lever 98 at 98A. A downwardly extending pin 100 is provided on the free end of the lever 98. This pin is in continual engagement with a cam surface 101 on a cam wheel 102. The cam surface 101 is provided with portions 101A—101D. The cam wheel 102 is fixed to the shaft 27 to rotate therewith. When the cam wheel 102 is stationary, the pin 100 of the lever 98 is in engagement with the cam portion 101A. When the cam wheel 102 begins to rotate through a cycle of operation, the cam portion 101B moves into engagement with the pin 100 and moves the lever 98 in a counterclockwise direction (Fig. 16) against the biasing action of the spring 99. When the lever 98 is moved in a counterclockwise direction (Figs. 15 and 16), the shaft 90 and the cam wheel 92 move therewith in a corresponding direction. When the cam portion 101C comes into engagement with the pin 100, the lever 98 stops its counterclockwise movement and is maintained in this position until the cam portion 101D comes into engagement with the pin 100. The cam portion 101D permits the spring 99 to move the pin 100 of the lever 98 into

engagement with the cam portion 101A during the rotation of the cam wheel 102. The movement of the pin 100 along the cam portion 101D moves therewith the lever 98, the shaft 90 and the cam wheel 92 in a clockwise direction (Figs. 15 and 16). When the pin 100 comes into engagement with the cam portion 101A, the lever 98, the shaft 90 and the cam wheel 92 are back in their respective normal positions and the rotation of the cam wheel 102 stops.

The counterclockwise movement (Fig. 15) of the cam wheel 92, during a cycle of operation of the cam wheel 102, performs the following functions in sequence. When the cam wheel 92 is stationary, the lower end of the pin 89 is in engagement with the cam portion 93A of the cam surface 93. As the cam wheel 92 begins to rotate in a counterclockwise direction (Fig. 15), the cam portion 93B moves into engagement with and raises the pin 89. By the time the cam portion 93C moves into engagement with the pin 89, the pin 89 has been raised to its uppermost position. The upward movement of the pin 89 pivots the pin 81 of the lever 80 into the plane of a top record on the turntable 34 and raises the pickup arm out of engagement with the top record on the turntable. While the pin 89 is being raised, as has just been described, the member 94 moves out of engagement with the spring 88 to move its free end into the path of the lever 81. Thereafter, the member 95 engages the lever 81 and moves it against the biasing action of the spring 88 in a counterclockwise direction (Fig. 15). The counterclockwise movement of the lever 81 transmits corresponding movement to the pickup arm 75 to move it in a corresponding direction to its outwardmost position shown in Fig. 1. While the pickup arm 75 is being raised and moved to its outwardmost position, the ribbon members 97 are moved by the cam wheel 92 to operate the record-elevating mechanism to be described hereafter.

After the functions just described have been performed by the counterclockwise movement (Fig. 15) of the cam wheel 92, a clockwise movement (Fig. 15) is imparted to the cam wheel 92 and this clockwise movement of the cam wheel performs the following functions. First, the ribbon members 97 are moved to operate the record-elevating mechanism to be described hereafter. During this operation, the member 95 is moved out of engagement with the lever 81 and the spring 88 moves the lever 81 in a clockwise direction (Fig. 15). The clockwise movement of the lever 81 transmits a corresponding movement to the pickup arm 75 and moves the pickup arm over the initial playing groove of the top record on the turntable 34. After the pickup arm is over the initial playing groove of the top record on the turntable, the member 94 engages the spring 88 and moves it out of engagement with the lever 81. Thereafter, the cam portion 93B permits the pin 89 to move downwardly into engagement with the cam portion 93A. This downward movement of the pin 89 permits the pin 81 of the lever 80 to move out of the plane of the top record on the turntable and permits the pickup arm 75 to be lowered into engagement with the initial playing groove of the top record on the turntable. When the cam wheel 92 finishes its clockwise movement it is in the position shown in Fig. 15.

Record-elevating apparatus

The apparatus for elevating the top record from the turntable 34 comprises two identical mechanisms mounted on the base plate 15 beyond the

periphery of the turntable 34 and diametrically opposite relative thereto, as shown in Figs. 1 and 2. Corresponding parts of each mechanism have been given the same number for convenience of description. One of these mechanisms is shown partly in section in Fig. 2, and will be described in detail. This mechanism includes an annular cam member 104 fixed to the bottom of the base plate 15. Cam portions 104A-104D are provided on the bottom surface of the cam member 104. A pedestal 105 having a tubular portion 106 is fixed to the top of the base plate 15 directly above the cam member 104. A pin 107, provided with a flanged portion 108 intermediate its ends, extends through the tubular portion 106 and the annular cam member 104 and is connected by a coil spring 109 to a suitable fixed object, preferably the cam member 104. As shown in Fig. 2, one end of the spring 109 is connected to the cam member 104 at 109A and its opposite end is connected to the flanged portion of the pin 107 at 109B. The spring 109 normally maintains the pin 107 in the position shown in Figs. 1 and 2. The spring connection of the pin 107 permits the pin 107 to be rotated about its axis and to be moved longitudinally along its axis. Both of these movements are against the biasing action of the spring 109. A head 110 is provided at the upper end of the pin 107. Intermediate the flanged portion 108 and the head 110, swivel plates 111 and 112 are connected to the pin 107 to rotate therewith. Both plates have free ends extending outwardly from their connections to the pin 107 and are angularly displaced relative to each other in a horizontal plane, as shown in Fig. 1. When the pin 107 is rotated in a clockwise direction (Figs. 1 and 2), the free end of plate 112 is adapted to move over the surface of the top record on the turntable 34 and the free end of the plate 111 is adapted to move between the two top records on the turntable 34. A knife portion 113 is provided at the free end of the swivel plate 111 to facilitate the movement of the plate 111 between records. A curved portion 114 is provided at the end of the swivel plate 112 which is connected to the pin 107. This curved portion 114 separates the bottom surface of the free end of the plate 112 a distance corresponding to the thickness of one record from the upper surface of the free end of the plate 111. The plates 111 and 112 are maintained in engagement with each other, as shown in Fig. 2, by spring elements 115 and 116. The spring 116 is placed between the flanged portion 108 and the bottom of the plate 111, and the spring 115 is placed between the top of the plate 112 and the head 110. The spring elements 115 and 116 permit the plates 111 and 112 to adjust themselves relative to each other in a vertical plane when they meet an obstruction such as a record of abnormal thickness.

A cam member 118 is affixed to the lower end of the pin 107. This cam member is cylindrical in shape and on the periphery of its upper surface there are formed cam portions 118A-118D. The spring 109 maintains these cam portions of the cam member 118 in continual engagement with the cam portions of the cam member 104. When the pin 107 is in its normal position, the cam portion 118A is in engagement with the cam portion 104A of the cam member 104, as shown in Fig. 2. A groove 121 is formed in the peripheral wall of the cam member 118. The ribbon members 97 are fixed to the groove 121 as by pins 121A and are adapted to be guided thereby.

The two record-elevating mechanisms located on diametrically opposite sides of the turntable are operated by the cam wheel 92 (Fig. 15) which is connected to them by the ribbon members 97. When the cam wheel 92 is driven in a counter-clockwise direction (Fig. 15) during a cycle of operation of the cam wheel 102, the cam members 118, the pin 107 and the plates 111 and 112 are rotated in a clockwise direction (Fig. 1) against the biasing action of the springs 109. As the cam members 118 are moved in a clockwise direction (Fig. 2), the cam portions 118A of the cam members 118 move into engagement with the cam portions 104B of the cam members 104. This lowers the pins 107 at the same time that they are moving in a clockwise direction (Fig. 2). The continued clockwise movement of the pins 107 moves the plates 112 over the upper surface of the peripheral edge portions of the top record on the turntable (Fig. 7). While these plates are still in engagement with the top surface of the top record on the turntable, the plates 111 move between the two top records on the turntable 34 (Fig. 7). Immediately thereafter, the plates 112 move out of engagement with the top record on the turntable and the cam portions 118A of the cam members 118 move into engagement with cam portions 104C of the cam member 104, as shown in Fig. 8. This permits the springs 109 to raise the pins 107 and therewith the plates 111. Since, at this time, the plates 111 are between the two top records on the turntable, the top record is raised by these plates 111, as shown in Fig. 8. The plates 111 of the record-elevating mechanisms are maintained in this position while the elevated record is gripped by a record-moving mechanism to be described hereafter and is lifted off of the plates 111. After the record-moving mechanism has performed its function, the cam wheel 92 begins to move in a clockwise direction (Fig. 15) back to its original position shown in Fig. 15. This clockwise movement of the cam wheel 92 permits the cam members 118, the pins 107 and the plates 111 and 112 to move in a counterclockwise direction (Figs. 1 and 2) in response to the biasing action of the springs 109. As the cam members 118 move in this counterclockwise direction (Fig. 8) the cam portions 118A move into engagement with the cam portions 104B of the cam member 104 and move the pins 107 and the plates 111 and 112 downwardly during their counterclockwise movement. Continued counterclockwise movement of the cam members 118, pins 107 and plates 111 and 112 in response to the biasing action of the springs 109 moves the plates 111 and 112 beyond the peripheries of the records on the turntable. Immediately thereafter, the cam portions 118A of the cam members 118 move out of engagement with the cam portions 104B and into engagement with the cam portions 104A. This permits the pins 107 and the plates 111 and 112 to return to their normal elevation shown in Fig. 2, in response to the biasing action of the springs 109. When the cam members 118 have reached the position shown in Fig. 2, one cycle of operation of the record-elevating apparatus is completed.

Record-moving mechanism

The record-moving mechanism is best illustrated in Figs. 1-6, 9 and 11-14 and includes a pair of brackets 130 fixed to and extending above the base plate 15, as shown in Fig. 1. To each of the brackets 130 there is affixed a bearing pin

131. To each of the pins 131 there is connected a member 132 which is rotatable about the common axis of the pins 131 in a position diametrically opposite to each other. Fixed to one of the members 132, as shown in Fig. 1, is a segmental gear 134. The segmental gear 134 is adapted to rotate the members 132 around the common axis of the pins 131. The mechanism for driving the segmental gear 134 will be described hereafter.

A housing 135 (Fig. 1), provided with a groove 136, is supported by extension portions 137 provided on the members 132, as shown in Fig. 1. This connection of the housing 135 to the members 132 is such that the housing 135 may be rotated around its longitudinal axis relative to the members 132. The housing 135 is adapted to be held in two stable positions relative to the members 132. This is accomplished by a spring-biased ball 138 which is adapted to engage, at different times, the notches 139 and 140, provided in the housing 135 (Fig. 5). The notches 139 and 140 are spaced 180° from each other. When the housing 135 is in the position shown in Fig. 5, the spring-biased ball 138 is in engagement with the notch 139. When the housing 135 is rotated about its longitudinal axis relative to the member 132, 180° from its position shown in Fig. 5, the spring-biased ball 138 comes into engagement with the notch 140. At one end of the housing 135, there is affixed thereto a short tubular shaft 142 to which is affixed a pinion gear 143. As will be described hereafter, the pinion gear 143 is adapted to cooperate in rotating the housing 135 about the axis of the shaft 142.

A pair of segmental gear members 144 and 145 are connected to the other end of the housing 135 by pins 146 and 147, respectively, and are adapted to be moved relative to the housing 135 in planes parallel to its longitudinal axis. The means for moving the gears 144 and 145 will be described hereafter. A pair of arms 148 and 149 are connected to the segmental gear members 144 and 145, respectively, by pins 150 and 151. The connections of the arms 148 and 149 to the gear members 144 and 145, respectively, permit the arms to move with the gears 144 and 145 in planes parallel to the longitudinal axis of the housing 135 and permit the arms 148 and 149 to move relative to the gears 144 and 145 and to each other in a plane normal to the longitudinal axis of the housing 135. Cam portions 148B and 149B are formed, respectively, on the ends of the arms 148 and 149, as shown in Figs. 1 and 5. When the gear 144 and therewith the arm 148 are moved in a clockwise direction (Fig. 1) and the gear 145 and therewith the arm 149 are moved in a counterclockwise direction (Fig. 1) to the position shown in Fig. 6 by means to be described hereafter, the cam portions 148B and 149B are moved into engagement with each other. With the portions 148B and 149B in engagement with each other, the opposite ends of the arms 148 and 149 are in gripping engagement with the upper and lower surfaces of an elevated record, as illustrated in Fig. 9. Record-gripping portions 148A and 149A of compressible material such as rubber are provided on the record-gripping ends of the arms 148 and 149, as shown in Figs. 5 and 9. When the arms 148 and 149 are in engagement with a record, as illustrated in Fig. 9, the record-gripping portions 148A and 149A are compressed to firmly grip the record.

The end of the housing 135, through which extension portions 137 tend the arms 148 and 149, is provided with an

13

opening 152 (Fig. 6). The opening includes portions 152A, 152B and 152C. When the arms 148 and 149 are in their outwardmost positions shown in Fig. 1, the arm 148 passes through the portion 152A of the opening 152, and the arm 149 passes through the portion 152C of the opening 152. When the arms 148 and 149 are in a record-engaging position, as shown in Figs. 3 and 9, the arms 148 and 149 pass through the portion 152B of the opening 152.

The segmental gears 144 and 145 are driven by a mechanism which includes a shaft 154 mounted in the housing 135 to rotate relative thereto, as shown in Figs. 1 and 5. A gear 155 is fixed to one end of the shaft 154 to rotate therewith and is adapted to operatively engage the segmental gears 144 and 145, as shown in Fig. 5. Gears 156 and 158 are fixed to the opposite end of the shaft 154 to rotate therewith, gear 158 being adapted to be driven by a segmental gear 157. The segmental gear 157, which has a gear 159 affixed to its hub, is pivotally connected to the base plate 15 in a suitable manner, such as that shown in Fig. 5. As shown in Fig. 1, the gear 159 is adapted to be in continual engagement with a gear 160. The gear 160 is fixed to a shaft 161 which is rotatably supported by a pair of brackets 162 and 163 (Figs. 1 and 2) which, in turn, are supported in a suitable manner from the underside of the base plate 15. To the opposite end of the shaft 161 there is affixed a segmental gear 165, as shown in Fig. 2. On the lower end of the bracket 163 there is pivotally connected a member 166 having a gear portion 166A and an extension pin 166B. One end of a spring 167 is connected at 167A to the member 166 and the other end is connected to a suitable fixed object, preferably the pin 167B in the bracket 28A. The spring 167 maintains the gear portion 166A in continual engagement with the gear 165 and the extension pin 166B in continual engagement with a cam surface 168 of the cam wheel 169, as shown in Fig. 2. The cam wheel 169 is fixed to the shaft 27 to rotate therewith. It is cylindrical in shape and, as shown in Fig. 12, the cam surface includes the cam portions 168A—168D. When the cam wheel 169 is stationary, the spring 167 maintains the member 166 in the position shown in Fig. 2. With the member 166 in this position, the end of the extension pin 166B is in engagement with the cam portion 168C and the members 166, 165, 160, 159, 157 and 158 are maintained in their respective positions shown in Figs. 1, 2 and 5. With the gears 157 and 159 in these respective positions, the gear 157 will be in engagement with the pinion gear 158 when the housing 135 and the arms 148 and 149 are in the positions shown in Figs. 1 and 5. Immediately after the top record on the turntable has been elevated in a manner previously explained, the cam portion 168A of the cam wheel 169 moves into engagement with the extension pin 166B and moves the member 166 in a clockwise direction (Fig. 2) against the biasing action of the spring 167. As the member 166 rotates in a clockwise direction (Fig. 2) the gear 165 and therewith the shaft 161 and the gear 160 are rotated in a counterclockwise direction (Fig. 2). The counterclockwise movement (Figs. 1 and 2) of the gear 160 moves the gears 159 and 157 in a clockwise direction (Figs. 1 and 5). When the cam surface 168D moves into engagement with the extension pin 166B, the gears 157, 158 and 155 have rotated sufficiently far to move the segmental gears 144 and 145 and the arms 148 and

14

149 to the positions shown in Figs. 3, 6 and 9. With the arms 148 and 149 in these positions, their respective cam portions 148B and 149B are in engagement with each other and the respective record-gripping portions 148A and 149A of the arms 148 and 149 are in engagement with an elevated record, as shown in Figs. 3 and 9. After the arms 148 and 149 are moved to and from either a record-reversing or a record-discard position, which movements will be described hereafter, the cam portion 166B moves into the path of the extension pin 166B. This permits the spring 167 to move the member 166 in a counterclockwise direction (Fig. 2) and the members 160 and 165 in a clockwise direction (Fig. 2). The clockwise movement of the gear 160 moves the segmental gear 157 into engagement with the pinion gear 158 to rotate the shaft 154 and the segmental gears 144 and 145 back to the position shown in Fig. 1 for moving the arms 148 and 149 out of the record-engaging positions shown in Figs. 3 and 9.

After the arms 148 and 149 have gripped an elevated record, they are then moved upwardly to either of two positions—a record-reversing position, as shown in dotted lines in Fig. 3, or a record-discard position in which position the arms 148 and 149 are adjacent a magazine 175. The magazine 175 is fixed to the base plate 15, as shown in Fig. 3. It includes a back plate 176 to which is affixed a pair of pins 177 and a pair of wall portions 178. The pins 177 are spaced in such a manner that when the arms 148 and 149 are moved to the record-discard position, they move between these pins, and the lower peripheral edge of the record gripped thereby is above the top surface of the pins 177. The pins 177 function to support records on their lower peripheral edges which have been released by the arms 148 and 149. There are provided rubber sleeves 177A on pins 177. The wall portions 178 are fixed to the upper end of the back plate 176 and function to guide the records released by the arms 148 and 149 as they slide on the pins 177 toward the back plate 176.

The mechanism for actuating the arms 148 and 149 for releasing a record gripped thereby includes a segmental gear 179 fixed to the shaft 180 to rotate therewith. The shaft 180 is rotatably supported by the brackets 181 and 182. The bracket 181 is supported by the base plate 15 and the bracket 182 (Fig. 14) is supported by a suitably stationary object not shown in the drawings. When the housing 135 and the arms 148 and 149 are moved to the record-discard position, the pinion gear 156, movable therewith is moved to the dotted-line position shown in Fig. 5. In this position, the pinion 156 is adapted to be driven by the segmental gear 179. The shaft 180 also has affixed thereto, as shown in Fig. 14, a gear 183 to rotate therewith. There is provided for driving gear 183 and shaft 180 a gear train consisting of drive gear 26A fixed to shaft 27, idler gear 26B fixed to shaft 184A and disposed to mesh with gear 26A, and pinion 184 also fixed to shaft 184A to be driven by gear 26B and to mesh with gear 183. Thus since gear 26 drives shaft 27, shaft 180 may be driven from shaft 27 in 1 to 1 ratio. One revolution of the gear 26 functions to move the arms 148 and 149 out of record-engaging position when these arms are in the record-discard position. One revolution of the gear 26 in a clockwise direction, driving through gears 26A, 26B and 184, rotates the gear 183 one revolution in a 75 counterclockwise direction. The counterclock-

wise movement of the gear 183 moves the segmental gear in a corresponding direction. The counterclockwise movement of the segmental gear 179, when in engagement with the pinion 156, moves the pinion 155, the shaft 154 and the pinion 155 in a counterclockwise direction, also. The counterclockwise movement of the pinion 155 moves the segmental gears 144 and 145 for moving the arms 148 and 149 out of record-engaging positions.

The movement of the housing 135 and the arms 148 and 149 from the full-line position shown in Fig. 3 to the record-reversing position or the record-discarding position previously referred to is performed by a mechanism which includes the segmental gear 134 fixed to the member 132 (Figs. 1 and 4), which has been previously described. The segmental gear 134 is in continual operative engagement with another segmental gear 185 fixed to a shaft 186 to rotate therewith. The shaft 186 is rotatably supported by a bracket 187 which is fixed to the bottom of the base plate 15, as shown in Figs. 4 and 5.

The shaft 186 also has affixed thereto an arm 189, one end of which is pivotally connected to a beam 190 at 190A (Fig. 4). Intermediate the ends of the beam 190, there is provided a pin 191. The opposite end of the beam 190 is provided with a bifurcated portion 190A as shown in Fig. 4, which serves as a sliding connection between the beam 190 and the shaft 27. The shaft 27 has affixed thereto a cam wheel 192 to rotate therewith. The pin 191 is adapted to be guided by cam groove areas 193—197 in the face of the cam wheel 192 to move the beam 190 over two different paths during different cycles of rotation of the cam wheel 192. The beam 190 is moved over one of these paths when the pin 191 is guided by the cam groove areas 193, 194, 195 and 197 and it is moved over a different path when the pin 191 is guided by the cam groove areas 193, 194, 196 and 197.

A member 199 is pivotally connected to the face of the cam wheel 192 in the common area of grooves 194, 195 and 196. As will be described presently, the member 199 is adapted to be moved to its dotted-line position (Fig. 4) at the beginning of a cycle of operation of the cam wheel 192, shown in Fig. 4 by a mechanism to be described presently. The member 199 is provided with an extension pin 200 which extends through a slot 201 provided in the cam wheel 192, as shown in Figs. 4 and 13. A pair of L-shaped levers 203 and 204 are pivotally connected intermediate their ends to an arm 205 fixed to the bracket 17 (Fig. 4). The right-hand end of the lever 203 is adapted to be moved into the path of the pin 200 (Figs. 4 and 13), and the right-hand end of the lever 204 is adapted to be moved into the path of the heel 58B of the member 58 shown in Fig. 10. The opposite ends of the levers 203 and 204 are swivelly connected to a lever 206 (Fig. 4). The opposite end of the lever 206 is connected to a manual control lever 207 in a suitable manner shown in dotted lines in Fig. 1. The lever 207 extends up through a slot 208 in the base plate 15 and has a knob 209 fixed to its free end. The lever 207 is adapted to be moved to two positions on the base plate marked "one-side" and "both-sides" respectively. When the lever 207 is moved to the "both-sides" position, it moves the levers 203 and 204 to their respective uppermost positions, shown in Fig. 4. In these respective positions, the lever 203 is out of the path of the pin 200 (Fig. 4) and the lever 204 is out of the path

of the member 58 (Fig. 10). When the lever 207 is moved to the "one-side" position, the levers 203 and 204 are moved to their respective lowermost positions shown in Fig. 4. When the lever 203 is in its lowermost position at the beginning of a cycle of operation of the cam wheel 192 and the pivotal member 199 is in its full-line position shown in Fig. 4, the lever 203 is adapted to move the pivotal member 199 to its dotted-line position.

- 10 If, at the beginning of a cycle of operation of the cam wheel 192, the pivotal member 199 is in its dotted-line position, the lever 203 will have no effect on the pivotal member 199. When the lever 204 is in its lowermost position (Fig. 4) at the beginning of a cycle of operation of the cam wheel 55 and the member 58 is in its dotted-line position (Fig. 10), the lever 204 will change the position of the member 58 to its full-line position (Fig. 10). If, at the beginning of a cycle of operation of the cam wheel 55, the member 58 is in its full-line position (Fig. 10), the lever 204 will have no effect on the member 58. Thus, it will be evident that, by moving the lever 207 to its "one-side" position, applicant's apparatus is adjusted to operate to discard a record from the turntable during each cycle of operation and when the lever 207 is moved to its "two-side" position, applicant's apparatus is adjusted to operate alternately to reverse a record on the turntable and to discard a record from the turntable during successive cycles of operation of the apparatus.

The rotation of the cam wheels 102 and 192 is so timed that, after the top record is elevated from the turntable, the arms 148 and 149 are moved into engagement with the elevated record, and the pickup arm 75 is moved to its outward-most position, the cam groove portion 194 of the cam wheel 192 moves into engagement with the pin 191. Thereafter, the continued rotation of the cam wheel 192 moves the beam 190 to pivot the arm 189 and therewith the segmental gear 185 in a counterclockwise direction (Figs. 4 and 5). The counterclockwise movement of the segmental gear 185 rotates the segmental gear 134 and the members 132 in a clockwise direction (Fig. 5) about the axis of the pins 131. The clockwise movement of the members 132 moves therewith the housing 135 and the arms 148 and 149 to move the elevated record off of the plates 111.

When the member 199 is in its full-line position shown in Fig. 4, the portion 199A thereof comes into engagement with the pin 191 and guides the pin into the cam groove portion 195. When the heel portion 199B of the member 199 comes into engagement with the pin 191, the member 199 is rotated to the dotted-line position shown in Fig. 4. When the pin 191 moves from the cam groove portion 194 to the cam groove portion 197 by the path of the cam groove 195, the movement of the beam 190 is limited in such a manner as to raise the arms 148 and 149 to the record-reversing position shown by dotted lines in Fig. 3. When the cam groove portion 197 comes into engagement with the pin 191, it moves the beam 190 to pivot the arm 189 and therewith the segmental gear 185 in a clockwise direction (Figs. 4 and 5). The clockwise movement of the segmental gear 185 moves the segmental gear 134, the members 132 and the housing 135 in a counterclockwise direction (Fig. 5) to lower the arms 148 and 149 back to the full-line position shown in Fig. 3, to place the record gripped thereby back on the plates 111. Thereafter, the plates 111 are

moved out of their respective record-supporting positions so that the top record again is supported on the turntable 34. On the next revolution of the cam wheel 192, the arms 148 and 149 are again raised when the pin 191 is guided by the cam groove portion 194. However, at the beginning of this revolution of the cam wheel 192, the member 199 is in the dotted-line position shown in Fig. 4. When the member 199 is in this position, the pin 191 is not obstructed by the portion 199A and is guided from the cam groove 194 to the cam groove 196. Since on this revolution of the cam wheel 192 the cam portion 194 guides the pin 191 over its full length, the beam 190 is moved further to the right (Fig. 4) than it was moved during the previous revolution of the cam wheel 192 and the arms 148 and 149 are moved correspondingly farther from the turntable 34. When the pin 191 engages the portion 199C, it pivots the member 199 from the dotted-line position shown in Fig. 4 to the full-line position shown in Fig. 4. While the pin 191 is being guided by the cam groove portion 196 to the cam groove portion 197, the segmental gear 179 engages the pinion gear 156 (Fig. 5) to move the arms 148 and 149 out of gripping engagement with the record to thereby deposit the record into the magazine 175. After the record that is gripped by the arms 148 and 149 is deposited into the magazine 175, the cam portion 197 comes into engagement with the pin 191 and begins to move the beam 190 to the left (Fig. 4) and to rotate the segmental gear 185 in a clockwise direction (Figs. 4 and 5). The clockwise movement of the segmental gear 185 moves the segmental gear 134 in a counterclockwise direction to lower the arms 148 and 149 to the positions shown in Figs. 1 and 5.

If, before rotating the cam wheel 192 through another cycle of operation, the lever 203 is moved into its lowermost position shown in Figs. 4 and 13, it is evident that during the succeeding cycles of operation of the cam wheel 192 and before the member 199 engages the pin 191, the pin 200 will move into engagement with the lever 203 and move the member 199 from the full-line to the dotted-line position shown in Fig. 4. As is clear from the description above, by this setting of the member 199 on the cam wheel 192, the arms 148 and 149 will again be moved to their record-discarding positions.

When the housing 135 and the arms 148 and 149 are elevated to record-reversing position previously described, they are rotated 180° about the longitudinal axis of the housing 135 by a mechanism shown in Figs. 1, 3 and 5 and which includes the pinion 143. With the pinion 143 in record-reversing position shown in dotted lines in Fig. 3, it is adapted to be rotated 180° about the axis of the shaft 142 by a mechanism which includes a segmental gear 212 (Figs. 1 and 5) rotatably fixed to a shaft 213 which is mounted on the bracket 162 and a bracket 214 fixed to the bottom of the base plate 15 (Figs. 1 and 5). The shaft 213 also has fixed rotatably thereto, a gear 215 (Figs. 1 and 5). The gear 215 is adapted to be driven by a corresponding gear 216 provided on one end of a shaft 217 which is rotatably mounted intermediate its ends on a bracket 218 fixed to the underside of the base plate 15, Fig. 5. The opposite end of the shaft 217 has a gear 220 which is adapted to be driven by a corresponding gear 221 rotatably fixed to the shaft 180. During a record-changing cycle, after the gear 143 assumes the dotted-line position shown in Fig. 3, the segmental gear 212 is moved into driving

engagement with the gear 143 by the rotation of the shaft 180. The rotation of the gear 143 by the segmental gear 212 rotates the housing 135 and the arms 148 and 149, 180° about the longitudinal axis of the housing 135 and turns over the record gripped by the arms 148 and 149 so that when the record is again lowered onto the record-elevating plates 111, its opposite side is exposed.

Mode of operation

The general mode of operation will now be described. In this mode of operation it will be assumed that the lever 207 is moved to the "both-sides" position shown in Fig. 1. First a stack of records is placed in centered position on the turntable 34. The turntable is manually lowered to the proper position by turning the knob 66 until the indicator 67 is moved to the number on the dial 68 (Fig. 18) corresponding to the number of records on the turntable 34. Thereafter the pickup arm 75 is placed in position for reproducing the top record on the turntable 34 and the apparatus is actuated into operation.

After the top record on the turntable 34 is reproduced and the stylus 78 of the pickup arm 75 (Fig. 15) moves into the tripping groove, a tripping mechanism (not shown) is actuated to initiate the rotation of the shaft 27, through a cycle of operation. The rotation of the cam wheels 102, 169 and 192 (Figs. 2 and 15) fixed to the shaft 27 is so timed during the cycle of operation that these cam wheels cooperate in carrying out a record-changing cycle. The first operation during the record-changing cycle is the lifting of the pickup arm 75 out of engagement with the top record on the turntable 34, and moving it to its outwardmost position shown in Fig. 1. This operation is brought about by the cam wheel 102 rotating the cam wheel 92 in a manner heretofore described. Thereafter the top record is elevated above the rest of the stack of records on the turntable. This is brought about by the cam wheel 92 (Fig. 15) moving the cam members 118, as has been previously described.

Immediately after the top record has been elevated, the cam wheel 169 (Figs. 2 and 12) functions to move the arms 148 and 149 into gripping relationship with the elevated record, as previously described. Thereafter the cam wheel 192 functions to move the members 132 and therewith the housing 135 and the arms 148 and 149 to a record-reversing position, shown in dotted lines in Fig. 3. Then the shaft 180, which is driven from shaft 27 by the gears 26A, 26B, 183 and 184, rotates the housing 135 and therewith the arms 148 and 149, 180° to reverse the record gripped by the arms 148 and 149. After the reversal of the record, the cam wheel 192 moves the members 132 and therewith the housing 135 and the arms 148 and 149 from the record-reversing position to the full-line position shown in Fig. 3, to return the reversed record onto the plates 111 (Fig. 13). Thereafter the cam wheel 169 functions to move the arms 148 and 149 out of gripping relationship with the reversed record and out to their outwardmost position shown in Fig. 1. Then the cam wheels 102 and 92 cooperate with the springs 109 and the spring 88 to move the plates 111 out of engagement with the pickup arm 75 in a clockwise direction. Thereafter the cam wheel 92 functions to lower the pickup arm 75 to move the stylus 78 into engagement with the initial playing groove of the top record on the turntable 34 after

which the rotation of the shaft 27 and the gear 26 stops and the reversed side of the top record on the turntable 34 is reproduced.

After the reverse side of the top record on the turntable 34 is reproduced and the stylus 78 of the pick-up arm 75 moves into the tripping groove, the tripping mechanism (not shown) is actuated again to initiate the rotation of the shaft 27 and the gear 26 through another cycle of operation.

The first operation which occurs during the cycle of operation, is the lifting of the stylus 78 of the pickup arm 75 out of engagement with the top record on the turntable 34 and swinging the pickup arm 75 to its outwardmost position in a manner previously described. During the outward movement of the pickup arm 75, the record-elevating plates 111 are operated to elevate the top record on the turntable 34, above the stack of records in a manner previously described.

Next, the arms 148 and 149 are brought into gripping engagement with the elevated record in a manner previously described.

Thereafter, the cam wheel 192 functions to move the arms 148 and 149 to record-discarding position after which the meter gear 44 (Figs. 2 and 12) functions with connecting mechanism to elevate the turntable 34. While the turntable is being elevated, the shaft 180, which is driven by the gear 183 rotates the gear 179 to move the arms 148 and 149 out of gripping engagement with the record, and the record is deposited into the magazine 175 in the manner previously described.

Next, the cam wheel 192 functions to move the arms 148 and 149 back to the full-line position shown in Figs. 1 and 3.

Thereafter the cam wheels 102 and 92 co-operate with the springs 109 and the spring 88 to move the plates 111 back to their normal positions and to move the pickup arm 75 inwardly from its outwardmost position to move the stylus 78 over the initial playing groove of the top record on the turntable 34. Then the pickup arm 75 and the stylus 78 are lowered into engagement with the record.

The next and following cycles of automatic operation are initiated by an automatic tripping mechanism (not shown) which is actuated each time the stylus 78 moves into a tripping groove of a record.

While there has been described what is at present considered the preferred embodiment of the invention, it will be obvious to those skilled in the art that various changes and modifications may be made without departing from the invention, and it is, therefore, aimed in the appended claims to cover all such changes and modifications as fall within the true spirit and scope of the invention.

What I claim is:

1. An automatic phonograph comprising a rotatable turntable for supporting a stack of records, a pair of movable members positioned beyond the periphery of said turntable and being movable in first and second planes, record-engaging means on each of said movable members for engaging the top record on said turntable adjacent the peripheral edge of said record when said members are moved in said first plane and for raising said record a limited distance from said turntable when said members are moved in said second plane and means operatively associated with said movable members and mov-

able under the raised record for elevating it from said record-engaging means.

2. An automatic phonograph comprising a rotatable turntable for supporting a stack of records, a pair of movable members positioned beyond the periphery of said turntable and being movable in first and second planes, record-engaging means on each of said movable members for engaging certain portions of the top record on said turntable adjacent the peripheral edge of said record when said members are moved in said first plane and for raising said record a limited distance from said turntable when said members are moved in said second plane and means operatively associated with said movable members and movable under the raised record for engaging other portions of it and elevating it from said record-engaging means.

3. An automatic phonograph comprising a rotatable turntable for supporting a stack of records, a pair of movable members positioned beyond the periphery of said turntable, said movable members being movable toward the center of said turntable and axially relative thereto, record-engaging means on each of said movable members at substantially the same level as the top record on said turntable for engaging certain peripheral edge portions of said top record on said turntable when said members are moved toward the center of said turntable and for raising said top record a limited distance from said turntable when said members are moved axially upward relative to said turntable, means operatively associated with said movable members and at substantially the same level as the top record on said turntable movable under the raised record for elevating it from said record-engaging means and elevating means operatively associated with said turntable for moving said turntable to maintain the top record thereon at substantially the level of said pair of movable members and said record-moving means.

4. An automatic phonograph comprising a rotatable turntable for supporting a stack of records thereon; elevating means operatively associated with said turntable for moving said turntable to maintain the top record thereon at a predetermined elevation; a pair of movable members positioned adjacent the periphery of said turntable and being movable in first and second planes; record-engaging means on each of said movable members for engaging peripheral edge portions of the top record on said turntable when said members are moved in said first plane and for raising said top record from said turntable when said members are moved in said second plane; means adjacent said turntable for clamping said elevated record and moving it from said record-engaging means; and driving means operatively associated with said elevating means, said movable members and said clamping means.

5. An automatic phonograph comprising a rotatable turntable for supporting a stack of records thereon; elevating means operatively associated with said turntable for moving said turntable to maintain the top record thereon at a predetermined elevation; a pair of members positioned at said predetermined elevation beyond the periphery of said turntable and being movable in first and second planes; first means operatively associated with each of said members and adapted to be brought into engagement with the surface of the top record on said turntable when said members are moved in said first plane; second means operatively associated with each of said

members and with said first means for moving between the two top records on said turntable when said members are moved in said first plane and for elevating said top record above said turntable when said members are moved in said second plane and means for flexibly connecting each of said first and second means with their respective associated members.

6. An automatic phonograph comprising a rotatable turntable for supporting a stack of records thereon; a pickup arm adapted to be moved into engagement with the top record on said turntable for reproducing it; elevating means operatively associated with said turntable for moving said turntable to maintain the top record thereon at a predetermined elevation; a pair of movable members positioned beyond the periphery of said turntable and being movable in first and second planes; record-engaging means on each of said movable members for engaging peripheral edge portions of the top record on said turntable when said members are moved in said first plane and for raising said record from said turntable when said members are moved in said second plane; driving means operatively associated with said pickup arm and said pair of movable members for moving said pickup arm and said movable members whereby said pickup arm is moved out of engagement with said reproduced record and said reproduced record is elevated from said turntable; and means operatively associated with said driving means for gripping said elevated record and moving it from said record-engaging means.

7. An automatic phonograph comprising a rotatable turntable for supporting a record thereon; a pair of movable members positioned beyond the periphery of said turntable and being movable in first and second planes; record-engaging means on each of said movable members for engaging peripheral edge portions of the record on said turntable when said members are moved in said first plane and for raising said record from said turntable when said members are moved in said second plane; a pair of movable arms positioned beyond the periphery of said turntable and adapted to be moved into clamping engagement with an elevated record on said record-engaging means; first means for moving said arms into said clamping position; second means for moving said arms, when they are in said clamping position, to record reversing position; third means for rotating said arms 180° about their longitudinal axis when they are in said record-reversing position for reversing the record clamped thereby; and driving means operatively associated with said members and said first, second and third means.

8. An automatic phonograph comprising a rotatable turntable for supporting a stack of records, a pair of movable members positioned beyond the periphery of said turntable and being adapted to engage peripheral edge portions of the top record on said turntable for elevating it therefrom, a pair of movable arms positioned beyond the periphery of said turntable and adapted to be moved into engagement with an elevated record on said movable members for removing a record therefrom and means operatively associated with said turntable, said movable members and said movable arms for maintaining the top record on said turntable at substantially the same level as that of the normal positions of said movable members and said movable arms.

9. An automatic phonograph comprising a rotatable turntable for supporting a stack of records, a pickup arm for reproducing a record on said turntable, a pair of movable members positioned beyond the periphery of said turntable and being adapted to engage peripheral edge portions of the top record on said turntable for elevating it therefrom, a driving means associated with said pickup arm and said movable members for moving said pickup arm beyond the periphery of said turntable and for moving said members to elevate said record, a pair of movable arms positioned beyond the periphery of said turntable and adapted to be moved into engagement with an elevated record on said movable members for removing a record therefrom and means operatively associated with said turntable, said movable members and said movable arms for maintaining the top record on said turntable at substantially the same level as that of the normal positions of said movable members and said movable arms.
10. An automatic phonograph comprising a rotatable turntable for supporting a stack of records thereon; elevating means operatively associated with said rotatable turntable for moving said turntable to maintain the top record thereon at a predetermined elevation; a pair of movable members positioned beyond the periphery of said turntable and being movable in first and second planes; record-engaging means on each of said movable members for engaging peripheral edge portions of the top record on said turntable when said members are moved in said first plane and for raising said top record from said turntable when said members are moved in said second plane; a pair of movable arms positioned beyond the periphery of said turntable and adapted to be moved into clamping engagement with an elevated record on said record-engaging means and thereafter adapted to be moved into record-reversing and record-discarding positions; first means for moving said arms into said clamping position; second means for moving said arms after they are in said clamping position, to record-reversing and record-discarding positions; third means for rotating said arms 180° about their longitudinal axis when they are in said record-reversing position for reversing a record clamped thereby; fourth means for moving said arms out of clamping engagement with a record when said arms are moved to said record-discarding position; and driving means operatively associated with said elevating means, said members and said first, second, third and fourth means.

JERALD D. WEAVER.
